(57) **CLAIM**

The ornamental design for a filler bar, as shown and described.

DESCRIPTION

FIG. 1 is a perspective view of a back of the filler bar; FIG. 2 is an inverted perspective view of the back of the filler bar shown in FIG. 1; FIG. 3 is a first perspective view of the front of the filler bar; FIG. 4 is a second perspective view of the front of the filler bar; FIG. 5 is an elevation view of the front of the filler bar; FIG. 6 is an elevation view of the back of the filler bar; FIG. 7 is a top plan view of the filler bar; FIG. 8 is a bottom plan view of the filler bar; FIG. 9 is an end view of the filler bar; and, FIG. 10 is an end view of the opposite end of the filler bar. Any shading shown in the figures is for illustrative purposes to show surface contours in the drawings only and forms no part of the invention.

1 Claim, 4 Drawing Sheets
